Primary Examiner—Janice E Seeger(74) *Attorney, Agent, or Firm*—Cislo & Thomas LLP(57) **CLAIM**

I claim the ornamental design for a bed headboard, as shown and described.

DESCRIPTION

FIG. 1 is a perspective view of my bed headboard;

FIG. 2 is a front view thereof;

FIG. 3 is a right side view thereof; and,

FIG. 4 is a left side view of my bed headboard.

The broken lines are for environmental purposes only and form no part of the claimed design.

The top of the bed headboard not shown, forms no part of the claimed design.
